UNITED STATES PATENT OFFICE.

IRVING HOCHSTADTER, OF FAR ROCKAWAY, NEW YORK.

PROCESS FOR BLEACHING FOODS.

1,412,523.

Specification of Letters Patent. Patented Apr. 11, 1922.

No Drawing.

Application filed April 6, 1921. Serial No. 459,088.

To all whom it may concern:

Be it known that I, IRVING HOCHSTADTER, a citizen of the United States, residing at Far Rockaway, in the county of Queens and 5 State of New York, have invented a certain new and useful Process for Bleaching Foods, of which the following is a specification.

This invention relates to a process for bleaching foods, and more specifically to a 10 bleaching process wherein sulphur dioxide (SO_2) or sulphurous acid or a salt of sulphurous acid is used, and the product then oxidized by hydrogen peroxide (H_2O_2) or other peroxide or peroxide giving com- 15 pounds non-injurious to food.

Processes for bleaching with SO_2 (which expression is used herein throughout to indicate SO_2 whether combined or uncombined to produce other compounds such as 20 sulphurous acid, sulphites or bisulphites, etc.) have been known for many years, but it has been a troublesome matter to eliminate the SO_2 remaining in the food after the bleaching operation has been completed. 25 The federal and various State pure food laws regulate and limit the SO_2 content in foods, and it is therefore highly desirable to make use of a process which can remove entirely or decrease the amount of such SO_2 , 30 without damaging the food.

The invention has accordingly as an object the provision of a process for removing SO_2 from food without damage thereto, and moreover with an improvement in its qualities. 35 It has as an object a process of bleaching in which SO_2 is used in conjunction with an agent which will assist in the bleaching operation.

The invention accordingly relates to a 40 process which comprises treating a food with SO_2 and then with H_2O_2 . More specifically, it relates to such a process wherein the H_2O_2 is added in amounts sufficient not only to oxidize the SO_2 , but also to itself bleach the 45 food.

The invention relates to the treatment of foods of various kinds generally, but for the sake of a specific description the following embodiment is given:

50 Gelatine which has been bleached with SO_2 may be further treated by hydrogen peroxide (H_2O_2) whereby not only additive effects of both bleaching agents are obtained, but also a combined effect which seems to 55 be due to the bleaching action of the peroxide on substances ordinarily not susceptible to bleaching action by SO_2 or H_2O_2 but

which are conditioned by the treatment with SO_2 so that they can be bleached by the subsequent treatment with the peroxide. More- 60 over, the mere additive effect of the SO_2 and H_2O_2 treatment secures a better bleaching of the gelatine than by the action of either agent alone since one is reducing and the other oxidizing in its action. It is advis- 65 able to add from 2 to 4% of ammonium hydroxide (NH_4OH) to aid and accelerate the bleaching process with H_2O_2 , and in case there should be any acidity in the product this can be neutralized with ammonium 70 hydroxide. The treatment with H_2O_2 is car- 75 ried out at a temperature of about 140° to 150° F. As a result of this treatment the sulphur dioxide present is entirely eliminated or reduced to the smallest possible amount, which would not be more than a trace.

As another embodiment of the invention, the following is given:

In the bleaching of cherries, SO_2 may be 80 added either uncombined as a gas or com- bined as a solution of sulphurous acid or of a sulphite such as sodium sulphite, which may be used in the cold or with the application of a little heat, and this treatment may be 85 continued from one to 24 hours, according to circumstances. The SO_2 remaining is then washed out with water as much as possible, and there will be left an amount of SO_2 ranging from mere traces to five to six 90 thousand parts per million. The cherries are then treated with H_2O_2 in the form of a three to four per cent solution in an amount sufficient to oxidize the SO_2 to H_2SO_4 or compounds of the same and also 95 to further bleach the cherries. In this bleaching operation the action is an oxidizing one as contrasted to the reducing bleaching action of the SO_2 . As a result, in this embodiment of my invention, also, the 100 sulphur dioxide present is entirely removed or reduced to the smallest possible amount which would not be more than a trace.

The sulphuric acid H_2SO_4 and compounds thereof formed in the above processes may 105 be then removed by washing or preferably by treatment with an alkali to neutralize the acid or both. The alkali used may be ammonium carbonate, ammonium hydroxide, sodium carbonate or sodium bicarbonate, 110 sodium hydroxide, calcium hydroxide, or any other alkali which will not be injurious to the food, a volatile alkali being particu- larly suitable since it can evaporate and leave

no impurity in the food product. The alkali furthermore aids in the bleaching action since hydrogen peroxide is particularly active as a bleaching agent in alkaline media.

- 5 In these processes the SO_2 and H_2O_2 bleach more permanently than SO_2 alone since the latter in its bleaching effect operates as a reducing agent whereas the SO_2 plus H_2O_2 operate with an oxidizing effect 10 due to the action of the H_2O_2 , also the SO_2 and H_2O_2 bleach more effectively than H_2O_2 alone. There will, therefore, be a combined 15 bleaching operation beginning with a reducing bleaching action and ending with an oxidizing bleaching action so that any decolorizing substance present in the food which will respond to an oxidizing or reducing action will be effectively attacked and bleached.
- 20 A large number of other foods may be similarly treated, such as fruit products, syrups, nuts, potatoes, apples, cereals, and in fact any kind of food susceptible to such treatment. The treatment of fruit products 25 by this method is particularly desirable since a bleaching operation is generally necessary and must be thorough in order to make the goods marketable. For example, in the drying of apples the latter are cut 30 into slices and then put into an evaporating chamber through which hot air at about 155° F. is passed in a careful manner to remove all but a small per cent of the water. During this operation the oxygen of the air 35 is very likely to cause the apples to discolor, and it is necessary to bleach them to make them white. If the bleaching operation is not effective in retaining the white color, the apples cannot command as high a price 40 on the market as pure white dried apples. By the treatment of this invention, the white color is made permanent and the SO_2 at the same time removed.
- 45 Any H_2O_2 which remains in the foods does no harm since it breaks up to form water and oxygen gas very rapidly.

By the term SO_2 in the claims I mean either sulphurous acid, a salt thereof, or an 50 SO_2 producing composition, and by the term H_2O_2 I mean hydrogen peroxide, a metallic or other peroxide, or a peroxide giving composition non-injurious to foods.

As many apparently widely different 55 embodiments of this invention may be made without departing from the spirit thereof, it is to be understood that I do not intend to limit myself to the specific embodiment thereof, except as indicated in the appended 60 claims.

I claim:

1. The process which comprises treating a food with SO_2 and then with H_2O_2 unmixed with additional acids.

2. The process which comprises treating a food with SO_2 and then with H_2O_2 unmixed with additional acids in sufficient amount to oxidize the SO_2 .

3. The process which comprises treating a food with SO_2 and then with H_2O_2 , and neutralizing the acid oxidation product formed with an alkali.

4. The process which comprises treating a food with SO_2 and then with H_2O_2 in sufficient amount to oxidize the SO_2 , and neutralizing the acid oxidation product formed with an alkali.

5. The process which comprises treating a food with SO_2 , washing in water to remove some SO_2 , and then treating with H_2O_2 .

6. The process which comprises treating a food with SO_2 , washing with water to remove some SO_2 , then treating with H_2O_2 , and neutralizing the acid oxidation product formed with an alkali.

7. The process of removing SO_2 from a food bleached thereby, comprising treating it with H_2O_2 in quantities sufficient to oxidize the SO_2 , and then neutralizing the acid oxidation product formed with a volatile alkali.

8. The process of bleaching a food comprising treating it with SO_2 and then with H_2O_2 in amounts sufficient to oxidize the SO_2 and to further bleach the food.

9. The process of bleaching a food comprising treating it with SO_2 , washing with water, and then treating with H_2O_2 in amounts sufficient to oxidize the SO_2 and to further bleach the food.

10. The process of bleaching a food comprising treating it with SO_2 and then with H_2O_2 in amounts sufficient to oxidize the SO_2 and to further bleach the food, and neutralizing the acid formed with an alkali.

11. The process of bleaching a food comprising treating it with SO_2 and then with H_2O_2 in amounts sufficient to oxidize the SO_2 and to further bleach the food, and then neutralizing the acid formed with a volatile alkali.

12. The process of bleaching a food comprising treating it with SO_2 , washing with water, and then treating with H_2O_2 in amounts sufficient to oxidize the SO_2 and to further bleach the food, and neutralizing the acid formed with an alkali.

13. The process of bleaching gelatine comprising treating the gelatine with SO_2 and then with H_2O_2 .

14. The process of bleaching gelatine comprising treating the gelatine with SO_2 and then with H_2O_2 in the presence of ammonium hydroxide.

In testimony that I claim the foregoing, I have hereunto set my hand this 21st day of March, 1921.

IRVING HOCHSTADTER.
